Primary Examiner—T. Chase Nelson*Assistant Examiner*—Karen Acker*(74) Attorney, Agent, or Firm*—R. Michael West(57) **CLAIM**

The ornamental design for a campfire wood stand, as shown and described.

DESCRIPTION

FIG. 1 is a perspective view of a campfire wood stand, showing my new design;

FIG. 2 is a front elevational view, thereof, the rear elevational view being identical, thereto;

FIG. 3 is a side elevational view, the opposite side elevational view being identical, thereto;

FIG. 4 is a top plan view, thereof;

FIG. 5 is a bottom plan view, thereof; and,

FIG. 6 is a perspective view in environment, the broken line representations of the firewood and the frying pan being included solely for illustrative purposes, forming no part of the claimed design.

The broken line representations of the foot pads shown in FIGS. 1, 2, 5, and 6 form no part of the claimed design.
